UNITED STATES PATENT OFFICE.

CLAUDE O. DUTRO, REGINALD W. KENT, AND GEORGE S. KENT, OF BURKBURNETT,
TEXAS.

TOOL FOR REMOVING SHACKLE BOLTS OF AUTOMOBILE SPRINGS AND THE LIKE.

Application filed May 28, 1921. Serial No. 473,333.

To all whom it may concern:

Be it known that we, CLAUDE O. DUTRO, REGINALD W. KENT, and GEORGE S. KENT, citizens of the United States, residing at 55 Burk Burnett, in the county of Wichita and State of Texas, have invented new and useful Improvements in Tools for Removing Shackle Bolts of Automobile Springs and the like, of which the following is a specification.

This invention relates to a tool for use upon automobiles and the like, the general object of the invention being to provide means for facilitating the removal of the 15 shackle bolts of the springs and the like.

Another object of the invention is to provide means for detachably securing the device to a part of the automobile with an 20 expandible part of the tool engaging another part so that when the expandible part is expanded the weight will be taken off of the bolt so that the same can be easily removed.

This invention also consists in certain other features of construction and in the 25 combination and arrangement of the several parts, to be hereinafter fully described, illustrated in the accompanying drawings and specifically pointed out in the appended claims.

30 In describing our invention in detail, reference will be had to the accompanying drawings wherein like characters denote like or corresponding parts throughout the several views, and in which:—

35 Figure 1 is a view showing the device in use.

Figure 2 is an enlarged view of the device itself.

Figure 3 is a sectional detail view.

40 As shown in these views the tool comprises a strap 1 having its ends bent upwardly to provide a channel-shaped member for engaging a spring or a part of the automobile. The member is clamped to the part with 45 which it engages by the screw bolt 2 which passes through a screw threaded hole in one of the bent up ends of the strap. A wrench engaging member 3 is swiveled, by means of the stud 4, to the central part of the 50 strap 1 and this member is provided with a

screw threaded socket 5 to receive the screw threaded bolt 6. The outer end of this bolt is pointed, as at 7, and adjacent this pointed end the bolt is provided with a transverse hole 8.

From the above it will be apparent that when the strap 1 is connected with a part of the frame of the automobile, as shown in Figure 1, with the bolt 6 engaging the spring, when said member 3 is rotated by a 60 wrench or the like the spring and frame will be forced apart due to the longitudinal movement of bolt 6 and thus the pressure of the parts upon the shackle bolt 9 will be removed so that said bolt can be easily withdrawn. Bolt 6 can be prevented from rotating by placing a pin or rod 8' in hole 8 but in most cases the said bolt 6 will be held against rotation by the frictional engagement of its pointed end with the spring or 70 other part.

The device can also be used in other situations where it is desired to force two parts away from each other.

It is thought from the foregoing description that the advantages and novel features of our invention will be readily apparent.

We desire it to be understood that we may make changes in the construction and in the combination and arrangement of the 80 several parts, provided that such changes fall within the scope of the appended claims.

What we claim is:—

1. A tool of the character described comprising a channel shaped member, a screw bolt adapted to pass through a screw threaded hole in the channel shaped member, a wrench engaging member swivelled to the channel shaped member and being provided with a screw threaded socket and a screw threaded bolt received in the socket as and for the purpose specified.

2. A tool for removing shackle bolts from vehicle springs comprising a channel shaped member designed to engage a portion of the 95 vehicle and being provided with a screw threaded hole, a screw threaded bolt passing through the screw threaded hole to clamp the channel shaped member to the desired portion of the vehicle, a stud swivelled to 100

the central portion of the channel shaped member, a wrench engaging member carried by the stud and being provided with a screw socket, a screw threaded bolt provided with

5 a transverse hole and a pointed end, said last mentioned bolt adapted to be received in the screw threaded socket and a rod re-

ceived in the transverse hole as and for the purpose specified.

In testimony whereof we affix our signatures.

CLAUDE O. DUTRO.
REGINALD W. KENT.
GEO. S. KENT.
